United States Patent Office

Des. 180,094
Patented Apr. 16, 1957

180,094

DESK

William S. Miller, Washington, D. C.

Application June 17, 1955, Serial No. 36,566

Term of patent 7 years

(Cl. D33—7)

I claim:

The ornamental design for a desk, as shown.
